AXEL A. LEANDER

By Attorney

Richard J. Cook

UNITED STATES PATENT OFFICE.

AXEL A. LEANDER, OF SEATTLE, WASHINGTON.

GAME DEVICE.

Application filed May 23, 1921. Serial No. 471,569.

To all whom it may concern:

Be it known that I, AXEL A. LEANDER, a citizen of the United States, and a resident of the city of Seattle, county of King, 5 State of Washington, have invented certain new and useful Improvements in Game Devices, of which the following is a specification.

This invention relates to game devices, 10 and has for its principal object to provide a device whereby a number of games may be played and which will not only furnish amusement and recreation in its use, but also will be of educational value, especially 15 to children, for the teaching of spelling, and the addition or subtraction of numbers.

A further object of the invention resides in the construction of a game device of the 20 above character, comprising an inclined base plate above which is mounted a circular horizontally revoluble table. The table has a peripheral retaining rim, and within this rim has circularly arranged, numbered and 25 lettered scoring pockets, wherein balls that are free to roll upon the disk may come to rest after a spinning operation of the disk. The disk is also provided near its center with an opening through which the balls 30 may occasionally drop onto the base plate, and the base is provided with pockets into which the balls may roll. It is also equipped with a series of rows of sockets for receiving indicia used in connection with the game.

In accomplishing the objects of the invention, I have provided the improved details of construction, the preferred forms of 35 which are illustrated in the accompanying drawings, wherein—

Figure 1 is a perspective view of a game device constructed according to the present invention.

Figure 2 is a plan view of the same.

Figure 3 is a vertical section through the 45 device, taken on line 3—3 in Figure 2.

Figure 4 is a perspective view of one of the indicia used in connection with the device.

Referring more in detail to the drawings—

1 designates the base plate of the device. This is of rectangular form, except at one end, which to enhance its appearance is curved radially. The base is supported in 55 an inclined position by means of a bar 2 that is secured transversely beneath the

curved end thereof, so that the balls, presently described, that are used in playing the game, when dropped onto the higher end of the board, will roll towards the forward 60 or lower end. Along the opposite sides and across the lower end of the base, rails 3, 3' and 4 respectively are secured. These extend above the surface of the plate, in order that they will prevent the balls from 65 rolling from the same.

Mounted upon a pedestal 5 that is fixed on the base plate 1 toward the higher end and in the central, longitudinal line thereof, is a circular table 6. This is provided concentrically with a hub portion 7 through which a vertical pin 8 is extended downwardly and into the pedestal 5 to retain the table functionally in position and rotatably mounted.

Located concentrically with respect to the pin 8, within the upper face of the table and near the hub portion thereof, is a shallow groove 9 adjacent which is an opening 10 through the disk. Also, arranged circularly 80 about the outer periphery of the disk, in spaced relation, are scoring pockets 12. There are, preferably, twenty six of these latter openings and each is individually designated by a letter of the alphabet and 85 also by a number. Within the upper face of the base plate, beneath the table, are grooves 15 and 16 respectively, which encircle the pedestal 5 and lead downwardly toward the lower end of the base plate and, at their 90 opposite ends, lead into pockets 17 and 18 which are located in spaced relation near the lower end of the base plate.

In playing the game, I prefer to use one or more small balls, of the character shown 95 at 19. These are placed upon the table 6 and when the latter is rotated, they will usually move to its outer edge where they are retained by the peripheral wall 13.

The grooves 15 and 16 are so located with 100 in the base plate that the balls 19, which are used in playing the games and which may drop through the opening 10 in the disk, will roll into one of these, and follow it along, and fall finally into one or the other of the 105 pockets 17 or 18.

Arranged in rows, preferably four, transversely across the lower end of the base plate, are circular sockets 20 within which circular blocks 21, of the character shown in 110 Figure 4, are adapted to be placed. These blocks each bear a letter on one side and a

number on the opposite side, and are provided in sufficient numbers that there will be three or more for each letter and numeral used.

5 In playing games with the device one or two of the balls 18 may be used and these are made of such size that they will if permitted to, drop through the opening 10. Occasionally, one of the balls drops through 10 the opening 10, but as a rule, they come to rest when the table stops rotating, within one of the scoring pockets 12. In playing most of the games for which the device is adapted, two balls, 19, are first placed within 15 the groove 9 in the table. Upon spinning the table, the balls will leave the groove and will roll to the outer rim thereof, and, as the table comes to rest, they will roll into pockets 12. This is made certain by sloping 20 the surface of the disk slightly toward the pockets from the rim 13. Occasionally, in this operation, one of the balls will drop into the opening 10 in the disk thence onto the base plate, and will finally lodge within one 25 or the other of the pockets, 17 or 18.

A game suitable for two players, which I call "Word building" is played in the following manner: Each player chooses a word; for instance, the words "America" and 30 "Chicago," and these words are constructed by placing the lettered blocks 21 within the first and third rows of sockets 20, as shown in Figure 2. The players then spin the disk in turn. If, when operated by the 35 first player, one of the balls should fall into the "A" opening of the table, that player places a block bearing the letter "A" in the socket 20 beneath the letter "A" in the word of the first column. If, in the use of the 40 table, one of the balls 18 should roll into the opening 10 onto the base plate and into the opening 17, the player is permitted one extra turn, while, if it rolls in the pocket 18, he is permitted two extra turns. If it is de- 45 sired, one ball may be used instead of two, thus lengthening the time of playing. The object of this particular game is to build the words, and the player who completes his selected word first wins the game.

50 Another game which aids in the learning of addition of sums is as follows: Each player in turn puts the two balls on the table

and revolves it; then adds together the designating numbers for the openings 12 in which the balls have stopped. The player who 55 first obtains a certain predetermined sum wins the game.

It is obvious that various other games can be played with the device, but only these two will be described, as they give an idea of 60 its use.

Having thus described my invention, what I claim as new therein and desire to secure by Letters Patent, is:

1. A game device of the character de- 65 scribed, comprising an inclined base plate provided near its lower end with a plurality of pockets with grooves leading thereinto from toward the upper end of the base; a table mounted above the higher end of the 70 base to be revolved in a horizontal plane and having a plurality of scoring pockets ar- ranged circularly about the edge thereof and having an opening therethrough near its center; balls adapted to roll on the table and 75 to come to rest within the scoring pockets or to fall through the opening onto the base plate, to be directed by said grooves into said pockets.

2. A game device of the character de- 80 scribed, comprising an inclined base plate provided with a plurality of rows of sockets, and with a plurality of pockets with grooves leading from the higher end of the base into the pockets, a table supported 85 above the higher end of the base plate and adapted to be revolved in a horizontal plane, said table having a plurality of scoring pockets arranged circularly about the edge thereof, each having a designating 90 character adjacent thereto, and having an opening therein near the center; balls adapted to roll on the table and adapted to come to rest within the scoring pockets or to fall through said opening to be directed 95 by the grooves of the base into its pockets and blocks adapted to be seated within the sockets of the base plate and bearing characters corresponding to the characters adjacent the scoring pockets.

Signed at Seattle, Washington, this 16th day of May, 1921.

AXEL A. LEANDER.
